UNITED STATES PATENT OFFICE.

MAURICE B. COLEMAN, OF WEST NEWTON, MASSACHUSETTS.

SANITARY CONNECTION.

1,226,469.

Specification of Letters Patent.

Patented May 15, 1917.

Application filed December 3, 1914. Serial No. 875,359.

To all whom it may concern:

Be it known that I, MAURICE B. COLEMAN, a citizen of the United States, and a resident of West Newton, Massachusetts, have 5 invented an Improvement in Sanitary Connections, of which the following description, in connection with the accompanying drawings, is a specification, like characters on the drawings representing like parts.

10 This invention relates to water closets and among other objects aims to provide simple and effective gas tight means for connecting the water closet with a soil pipe and floor.

The character of the invention may be 15 best understood by reference to the following description of an illustrative embodiment thereof shown in the accompanying drawing, wherein:

Figure 1 is a horizontal section through 20 the base of the bowl of a water closet embodying the invention;

Fig. 2 is a vertical section taken on the broken line 2—2 of Fig. 1; and

Fig. 3 is a section taken on the broken 25 line 3—3 of Fig. 1.

Referring to the drawing, 1 designates a floor of concrete or other appropriate material having a hole therein for receiving a soil pipe 3 of iron or other material projecting somewhat above the level of the 30 floor; 5 designates the neck of a bowl of earthenware or other material of a water closet of usual construction. Projecting from the neck 5, preferably integral therewith, is a base 7 formed to present a recess 9, an outer encircling rim 11 and a depending ring 13.

Encircling the soil pipe is a flange 15 having a channel 17 for receiving the base ring 40 13. The channel may be filled with soft white lead, putty or other suitable material. When the parts are assembled the base ring 13 enters the putty filled channel and constitutes a permanent water-seal, gas-tight 45 joint serving effectively to guard against the escape of sewer air.

Also encircling the soil pipe is a ring 19 of iron or other appropriate material adapted to bear against a gasket 21 of rubber composition or other yielding elastic 50 material. The ring is connected to the flange by screws 23. Preferably the flange and ring are formed to present opposed inclined surfaces which when the ring is forced 55 downward by said screws will tend to press the gasket toward and into intimate engage-

ment with the soil pipe and form a permanent water-seal, gas-tight joint and constitute the connection between the flange and the soil pipe. The material and pressure of 60 the gasket 21 against the soil pipe are such that in the event of any settlement in the floor or pipe the gasket will slide along said pipe and prevent any dislocation of the parts such as might invite leakage. 65

The flange 15 may be secured to a floor by expansion bolts 25 threaded into anchor sleeves 27 set into the floor. If it is not convenient to introduce the sleeves into the floor, as for example in the case of a wood 70 floor, usual wood screws may be substituted for the expansion screws 25.

To prevent any possibility of leakage between the bottom of the flange and the floor the former is recessed to receive a gasket 33 75 of rubber composition or other appropriate material. When the flange is screwed to the floor the gasket is pressed tightly against the same, forming a permanent seal against leakage of floor-water beneath the flange, 80 thence to and along the soil pipe to the floor below.

To lock the closet base 7 firmly to the floor it is connected to the flange 15 by wedge means shown herein as comprising wedge 85 shaped projections 29 on the flange designed to interlock with corresponding wedge shaped projections 31 on the base of the closet. These wedge projections are distributed at intervals circumferentially of said 90 flange and base, leaving spaces between them, thereby permitting the base to be placed over the flange and then given a rotative adjustment, causing the base projections to engage the flange projections. In 95 the course of this rotative adjustment their wedge action will cause the ring of the base to be pressed down into the putty in the flange channel and cause the rim of the base to be pressed securely against the floor and 100 to be firmly secured to the flange. The wedge projections are so located and arranged that when the rotative adjustment of the base is completed the bowl will be in a proper position to present the flushing water inlet in registration with the flushing water supply pipe. The connection of said pipe with said inlet prevents unlocking rotation of the base. 105

By the wedge connection described the 110 base is secured to the flange by a simple adjustment and by devices which are con-

tained within the base and concealed from external view. Consequently the outer surface of the base may be smooth and uninterrupted without the presence of any bolt holes, bolts, nuts, washers or other fastening devices which are unsightly, and are unsanitary as they invite the accumulation of dirt and filth which is difficult if not impossible to remove.

10 It will be observed that the top of the soil pipe is higher than the outer wall of the flange. Consequently if there is any defect in the putty connection between the base ring and flange the water will escape 15 over the outer wall of the flange downward and thence outward between the rim and the floor, thereby serving as a telltale of the leak.

Preferably the wedge projections for the 20 base are formed integrally therewith, thereby reducing the number of parts necessary to assemble and contributing to the simplicity and strength of the construction. The parts may be readily assembled without requiring the services of a skilled mechanic.

Having described one illustrative embodiment of the invention without limiting the same thereto, what I claim as new and desire to secure by Letters Patent is:

Copies of this patent may be obtained for five cents each, by addressing the "Commissioner of Patents, Washington, D. C."

The combination with a water-closet base 30 7 having a rim 11 forming a recess 9 in said base, of a soil pipe 3 projecting up into said base, a ring 13 depending from said base and spaced from said pipe to form a water-seal pocket between them, a flange 15 35 encircling said pipe having a channel 17 therein, a packing confined between said channel and ring to prevent leakage of water from said pocket between them, a member 19 adjustably connected to said flange, 40 a packing 21 embracing said pipe and confined between said member and flange to prevent leakage of water from said pocket along said pipe while permitting movement of said pipe relative to said flange, a packing 33 at the bottom of said flange, and means 25, 27 to connect said flange to a floor and press said packing 33 tightly against said floor to prevent water from flowing along the floor to said pipe.

In testimony whereof, I have signed my name to this specification, in the presence of two subscribing witnesses.

MAURICE B. COLEMAN.
